UNITED STATES PATENT OFFICE

2,457,249

TOY

Sidney K. Lipschitz, New York, N. Y.

Application August 23, 1946, Serial No. 692,637

1 Claim. (Cl. 46—22)

1

This invention relates to toys and more particularly to those of a constructional character by means of which animals or other small figures are produced by the assembly of various elements or parts.

An object of the invention is to provide a toy of this character composed of a plurality of separable parts adapted to be fitted together without the use of tools, and by a small child, and which will result in the figure of an animal or the like. The invention contemplates the provision of means by which the several parts are removably fitted together such means being of concealed nature and while securely holding the parts of the figure in assembled relationship, will nevertheless readily permit the dismantling of the toy when desired.

Another object of the invention is to provide, in a toy of this character, means by which the limbs, head, tail or other parts of a toy animal may be maintained in pivotal relationship with respect to body parts of the toy, the pivot elements for the various parts being concealed from view yet readily insertable and removable when desired.

Still another object of the invention is to provide in a toy of this character, a plurality of elements which can be interchangeably used to provide different animal or other figure representations.

More particularly, the invention contemplates the provision of a toy consisting of a pair of spaced body elements of sheet-like nature held in spaced relation by a plurality of pins or dowels frictionally maintained in recesses extending only partly through the body elements, the recesses in one of the body elements being spaced farther apart than those in the other body element to thereby place the pins or dowels under stress, thus aiding materially to hold them in place; and in the employment of legs, head, tail or other elements of the figure located between the body elements and pivotal upon the pins or dowels.

In the accompanying drawing, wherein an illustrative embodiment of the invention is disclosed, Fig. 1 is a face view of one of the disks which form the body of the toy; Fig. 2 is a similar view of the second body disk; Fig. 3 is a sectional view through one of the disks, showing one of the pivot pins inserted in the disk and the second pivot pin removed from the recess in the disk; Fig. 4 is a side view of the assembled toy animal; Fig. 5 is a front elevation of the toy; Fig. 6 is a side elevation of the head; Figs. 7 and 8 show the foreleg and hind leg respectively, and Fig. 9 shows the tail.

2

In the embodiment of the invention shown in the drawing, 1 indicates one of the body parts of the toy. The same is shown of disk-like or circular shape and it can be composed of any suitable, relatively flat, sheet material such as wood, fibre-board or plastic or any other material from which these disks can be speedily and economically stamped, molded or cut. While this disk, and its companion disk shown at 2, are shown of circular form, they may be made in other shapes as will be understood, the circular form being shown since it is readily interchangeable for use as the bodies of various kinds of animals and the like.

15 The disk or body part shown at 1 is provided with a pair of recesses seen at 3 and 4, these recesses extending only partly through the disk and being adapted to receive the ends of the pins 7 and 8 which serve as pivot members for the legs, head and tail of the animal. The pins 7 and 8 may be short lengths of doweling or the like, and are such a diameter that they fit snugly into the recesses 3 and 4 and are thus held therein. If desired, they may be glued or otherwise permanently attached to one of the disks, the other disk being removable.

Disk 2 is similar to that shown at 1 and is also provided with a pair of recesses 5 and 6 which also extend only partly through the disk. It 30 will be noted that recesses 5 and 6 are spaced farther apart than the recesses 3 and 4. This arrangement is such that when the pins 7 and 8 are fitted in the recesses 3, 4, 5 and 6, the pins will be placed under stress and will thus hold 35 themselves firmly in the recesses and serve to connect the two body parts 1 and 2 together and hold said parts in the spaced relationship clearly noted in Fig. 5.

At 9 is shown the head of the toy animal, the 40 same being provided at one end with the aperture 19 of a size enabling it to be fitted on one of the pins 7, 8. The foreleg is shown at 13, there being two of these elements provided. At the top each foreleg is formed with the aperture 14 to fit 45 about one of the pivot pins. The rear or hind leg is shown at 16, two of these elements being used, and the same is provided with the aperture 17.

At 12 is shown the tail, the same having the 50 aperture 19 fitting about the rear pivot pin 8. To enable the various parts of the toy to move without binding, yet frictionally resist a too-free pivotal movement whereby the legs, head and tail will hold any position in which these parts 55 are placed, spacing washers of fibre, felt, cork

or similar material are provided, the same being shown at 11, 15, 18 and 20. These washers may be separate elements which are slipped on the pins 7 and 8 during the assembly of the parts of the toy, or they may be adhesively or otherwise secured to the faces of the several parts of the toy around the pin-receiving apertures therein.

From the foregoing, the manner of assembly and use of the toy will be readily understood. Since the parts of the toy are, when assembled, held together without the use of glue or other similar fastening means, the toy is distributed in dis-assembled or so-called "knock-down" condition. The child will find it very simple to assemble the toy by inserting one end of each pin 7 and 8 into the recesses in one of the disks 1 and 2, if said pins are not provided in permanent attachment to said disk. The legs, head and tail are then slid in place on the pins 7 and 8, and finally the second disk or body part is fitted in place on the pins and the toy is then completely assembled. Since the legs, head and tail are freely pivotal upon the pins 7 and 8 these parts may be pivoted to position them in various postures to amuse the child, and the four legs with which the toy is provided enable it to be placed in a standing position on any suitable surface.

The circular or disk-like shape of the body sections 1 and 2 enable these parts to be interchangeably used for the production of many different animals or other figures. Thus, two of these body parts may be provided together with an assortment of legs, arms, paws, heads and tails and by attaching these various extremities to the body parts in the manner explained, various types of animals, birds and other articles will result and will tend to keep a child amused and serve to be instructive to it.

It is to be noted that the pins 7 and 8 have their ends fitted in the recesses 3, 4, 5 and 6 which extend only partly through the disks in which these recesses are formed. The result is that when the toy is assembled the pins are hidden from view and the outer surfaces of the disks or body parts 1 and 2 are smooth and uninterrupted by screw or bolt heads or other protruding parts.

As previously explained, all of the parts of the toy may be readily stamped, cut or molded from suitable inexpensive material and the toy can be speedily and economically manufactured and inexpensively sold.

While I have herein shown the parts of the toy as being of certain shapes to enable the exaggerated figure of an animal such as a horse, to be produced, many different types of animals, birds, or the like can be made by changing the configuration of the parts. Hence, I do not limit the invention to the shape of the parts disclosed or to the materials from which said parts are fabricated and I contemplate other modifications as comprehended by the scope of the claim appended hereto.

What I claim is:

In a constructional toy, a pair of body sections, limbs pivotally mounted between the sections, pivot pins on which the limbs are mounted and which connect the body sections together, the body sections having recesses in their inner faces only, said recesses extending only partly through the body sections, the ends of the pivot pins being frictionally and removably fitted into said recesses, the recesses in one of the body sections being spaced slightly farther apart than those in the other body section so that the pivot pins will be placed under stress when fitted in the recesses in the two body sections.

SIDNEY K. LIPSCHITZ.
